SPRING CUSHIONED ARTICLE OF
FOOTWEAR

William Benner, Jr., Park City, Mont.

Application February 23, 1949, Serial No. 77,811

1 Claim. (Cl. 36—7.8)

1

This invention relates to footworn devices for assisting in the locomotion and/or exercising of the wearer during walking, running or jumping, and more specifically to such devices which employ resilient cushioning means, which alternately store up and release energy, during locomotion of the wearer.

An important object of the invention is to provide a spring-cushioned article of footwear of this nature which is so constructed that there will be substantially no fatiguing of the wearer because of and during use of the article of footwear.

Another important object is to provide such an article which resiliently supports the foot of the wearer off the ground the center of the area of resiliency being partly below the heel and partly below the sole just forwardly of the heel, thus bridging portions of the sole and heel, whereby the wearer is not apt to be thrown backwards while jumping, for example, while using two of the articles attached to his feet.

Still another important object is to provide a particularly strong article of this kind yet possessing great resiliency insofar as the spring portion is concerned. While the footwear is described as adapted for locomotion, such as in walking, running or jumping, it should be noted that it is also well adapted to cushion the descent of the wearer when he strikes the ground, feet first, as in descents by way of a parachute.

A further object is to provide such an article of footwear, worn by players of games, at basketball, for example.

Other objects and advantages of the invention will be apparent during the course of the following detailed description of the invention taken in connection with the accompanying drawing, forming a part of this disclosure, and in which drawing:

Fig. 1 is a top plan of the new article of foot-wear.

Fig. 2 is a view partly in side elevation and partly in vertical longitudinal section thereof, including a lower plate portion.

Fig. 3 is a bottom plan of the bottom plate portion.

The new spring-cushioned article of footwear comprises an upper plate portion 10, a lower plate portion 11 and a coil spring 12.

From Figs. 1 and 2, it will be seen that the upper plate portion 10 is elongate, having a forward end section 13, rearward section 14, intermediate section 15, a substantially flat upper face 16 and a substantially flat lower face 17 and the

plate portion 10 is normally disposed substantially horizontal. It may be provided with an opening 18 from face to face and disposed intermediate its ends, preferably at the section 15, a suitable number of strap slots 19 preferably at the section 14, a suitable number of depending strap eyes 20 preferably at the section 13 and secured to the lower face 17, and a heel abutment 21 extending upwardly from the upper face 16 and disposed intermediate the sections 13 and 14 (as at the section 15 but nearer the section 14 than the section 13). Preferably this abutment has a rear face 22 the vertical plane of which is normal to the face 16.

In Figs. 2 and 3, the lower plate portion 11 is shown as a substantially flat member but the extremities of its forward end section 25 and rearward end section 26 may be turned up slightly, as at 27. It has an intermediate section 28, an upper substantially flat face 29 and lower, substantially flat face 30. From the lower face 30 may project caulks 31. The portion 10 may be provided with an opening 32 in its intermediate portion. Normally, the portion 11 substantially parallels and is spaced below the portion 10 (mostly below the intermediate portion 15 of the latter) and, because it is preferably shorter and narrower than the portion 10, it may be disposed within the vertical plane of the edges of the portion 10.

I prefer to construct the portions 10 and 11 of structural steel, with the portion 10 substantially five-sixteenths inch thick and the portion 11 substantially one-quarter inch thick.

It will be noted in Fig. 2 that the elongated coil spring 12 has its longitudinal axis normally vertically disposed and that the convolutions form a helix with the width of the coil least at the bottom portion 35 thereof. In addition, the diameter of the material (preferably structural silicon steel) forming the coil spring is progressively less from the upper portion 36 to the lower or bottom portion 35 thereof. For example, the spring 12 may be constructed of a rod having a maximum diameter of substantially three-eighths inch (forming the first lowermost convolution 37) and tapering uniformly to five-eighths inch for the first uppermost convolution 38. Preferably the normal distance between any two adjacent convolutions is the sum of the diameters of these said convolutions, divided by 2. The terminal convolutions 37 and 38 must be machined to provide flat faces for attachment, as by welding, to the respective portions 10 and 11. Preferably, fusion welding is provided, em-

ploying from a three-eighths inch to one-quarter inch conventional fillet weld.

It will be noted that the spring 12 is connected to the plate 10 so that it bridges the rearward and intermediate sections 14 and 15, with the heel abutment 21 within the vertical plane of the spring 12. This places a portion of the heel of the wearer over the spring rather than the entire heel outwardly of that plane, since the forward edge of the heel is adapted to contact the face 22 of the abutment 21. As a consequence, there is less possibility of the plate portion 10 tipping accidentally when the footwear is being worn, the plate portion 10 is less apt to be torn loose from the spring 11 and there is less fatigue than if the spring were disposed substantially centrally of the ends of the plate portion 10.

The plate portion 11 is wide and long enough, as is apparent in Figs. 2 and 3, to provide a complete covering and foundation for the bottom of the spring 12, and is, in effect, an auxiliary heel, rather than a mere device upon which to anchor the lowermost terminal convolution. Hence, the caulks 31.

The weight of the entire assembly is negligible so that it does not interfere with locomotion.

In attaching the article of new footwear to a shoe for example, the wearer positions the front edge of his shoe heel against the face 22 of the abutment 21, thus placing his heel within a part of the vertical plane of the spring 12 and may then detachably secure the article to his shoe as by a conventional buckled strap (not shown) extending through the slots 19 along the adjacent face 17 and upwardly across the shoe upper at 35

the instep, while another conventional buckled strap (not shown) may be threaded through the eyed portions 20 extend across the face 17 and thence upwardly and over the upper at the waist 5 of the foot.

Various changes may be made to the form of the invention herein shown and described without departing from the spirit of the invention or scope of the claim.

10 What is claimed is:

In a spring-cushioned article of footwear a normally substantially horizontally-disposed upper plate portion, a lower plate portion spaced below and normally substantially paralleling the upper plate portion, and an expansion coil spring, having a normally vertical longitudinal axis, joined to said plate portions, the material forming the convolutions of said spring being progressively of less diameter from the top to the bottom 15 of said spring.
